UNITED STATES PATENT OFFICE

THOMAS F. KERLIN, OF SOLVAY, NEW YORK

FRAME UNIT FOR SCAFFOLDING, SHORINGS, CONCRETE FORMS, AND THE LIKE

Application filed July 14, 1931. Serial No. 550,727.

This invention has for its object a frame unit by means of which scaffolding, shoring supports, forms for concrete work and the like can be readily constructed and knocked down and the units re-used, which unit consists of a main member which may be used as a strut or a cross beam and end members or coupling pieces, one of which is interchangeably mountable either on the end of the main member or on the side thereof at various heights, so that a frame work for scaffolding, shorings, towers, etc., of almost any form can be made from the units.

The invention consists in the novel features and in the combinations and constructions hereinafter set forth and claimed.

In describing this invention reference is had to the accompanying drawings in which like characters designate corresponding parts in all the views.

Figure 1 is a side elevation of this unit, a contiguous portion of another unit being also shown.

Figure 2 is a side elevation, taken at a right angle to Figure 1.

Figure 3 is a fragmentary longitudinal sectional view of two units coupled together.

Figure 4 is a fragmentary elevation showing two of the main bodies of the units spliced together.

Figure 5 is a fragmentary plan view of a structure for supporting the forms for a square pillar.

Figure 6 is an elevation showing the units used for supporting the forms for cement walls.

Figure 7 is a lengthwise sectional view of one of the units and contiguous parts showing one use of the same when a unit is arranged in horizontal position and coupled by means of the coupling pieces to upright units.

Figure 8 is a detail view of one of the coupling pieces.

This unit comprises, generally a main member formed with a lengthwise slot and having a lengthwise tongue at one end in line with the slot and a socket at its other end for receiving a coupling piece in the form of a tongue and a coupling piece interchange-

ably mountable on the tongue and on the side faces of the body, this coupling piece having a stem which is bifurcated for receiving the tongues and a head for engaging a side face of the main body with the bifurcated stem extending laterally from the main body to receive a tongue of another unit.

1 designates the main body which is formed up of opposing strips spaced apart to form a lengthwise slot 2, these strips being usually some form of angle iron, they being preferably channel irons arranged with their backs opposed to each other to form the side walls of the slot 2. The strips are held spaced apart to provide the slot 2 in any suitable manner as by spacers 3.

4 designates a tongue at one end of the body, the tongue being provided with a bifurcated base 5, the branches of which lie in the end portions of the channels of the strips and which are secured to the bottom of the channel in any suitable manner as by rivets 6. The tongue 4 is in line with the slot 2.

7 is the socket member arranged at the opposite end of the main body 1 to that on which the tongue 4 is located, this being arranged to receive the tongue 4 of another main body or a demountable tongue or coupling piece 8 in order to adapt this end of the body to receive a T-shaped coupling piece to be presently described. The socket member 7 is in the form of a head or box formed with a socket in line with the slot 2 and having legs or plates 9 arranged to lap the bottom flanges of the channel iron 1 and secured thereto in any suitable manner as by rivets 10.

11 is a coupling piece having a bifurcated stem or leg 12 and a head 13, the bifurcated leg being for the purpose of receiving the tongue 4 and to be detachably secured thereto in any suitable manner as by bolts 14. This coupling piece 11 is usually T-shaped and is interchangeably mountable on the end of the body 1 with its bifurcated leg receiving the tongue 4 or with its head abutting against a side face of the body 1, so that its leg projects at a right angle to the body 1 for receiving the tongue 4 of another unit arranged in horizontal position. The head is preferably formed with corrugations as shown at 15 for

coacting with teeth 16 extending lengthwise of the body 1 on opposite sides of the slot, the head being provided with perforations 17 and 18 for receiving clamping bolts, the perforations 17 being arranged to receive spaced apart bolts 19 straddling the body 1, when the head is clamped to the main body 1 as shown in the upper end of Figure 7, the bolts extending through a washer plate 20. The perforation 18 is threaded and arranged centrally of the head 11 and arranged to receive a clamping screw 21 (Figure 2) extending through the slot 2. When in this position, as the coupling piece 11 is held on by one bolt, the interlocking corrugations 15 and teeth 16 are engaged.

The socket piece 7 is also formed with teeth 16 forming continuations of the teeth 16 of the main member 1.

20 In Figures 1 and 2, the unit is shown as in upright position or as a pillar with the socket member 7 serving as a foot piece and the T shaped coupling member 11 as coupled to a member 1 arranged in horizontal position by the bolt 21 extending through the slot 2 of the body of the main member arranged in horizontal position. The construction shown in Figures 1 and 2 is adapted to support shorings for floors.

30 In Figure 3, two main members are shown as arranged end to end and coupled together by the socket or foot piece 7 at the end of one main member and the tongue 4 at the end of the other main member.

35 In Figure 4, two main members are shown as lapping each other or spliced together by having the teeth 16 engaged and the two members clamped together through the slots 2 by means of bolts 22.

40 In Figure 5, an arrangement is shown of the horizontal members when the units are used to form shorings or a mould for a square pillar. The T shaped pieces 11 at the ends of each member are coupled or secured to a side face of the adjacent members in the manner shown in the upper end of Figure 2. When a T shaped piece is to be provided at each end of a main member, a tongue or coupling piece 8 is inserted in the foot piece or 45 socket member 7, as shown in the lower end of Figure 7 so that a T shaped coupling piece can be mounted on the projecting end of the coupling piece or tongue 8 and bolted thereto.

50 In Figures 6, the form is shown for supporting the shorings of a concrete wall and the horizontal members are secured to the vertical members as shown at 25, also spreaders 26 are shown as connected to the ends of the bolts which secure the horizontal members 1 to the upright members 1.

55 It is obvious that by reason of this unit consisting of a main body 1 of channel iron having the tongues 4 and socket piece 7 and the T shaped coupling piece 11 and tongues 8, an 60 indefinite number of arrangements is possi-

ble for forming walls, columns, floor forms, wall forms, scaffolding, towers, etc.

What I claim is:

1. A frame unit for scaffolding, shorings, forms and the like comprising a main body 70 forming with a lengthwise slot and a tongue at one end of the body in line with the slot, and a T shaped coupling piece interchangeably mountable on the end of the body and on the sides thereof said coupling piece having 75 its leg bifurcated for receiving the tongue, and its head being provided with openings for receiving clamping means when the coupling piece is arranged with its head against a side face of the body, one of said openings 80 being arranged to come in line with the slot.

2. A frame for scaffolding, shorings, forms and the like comprising a main body formed with a lengthwise slot having a tongue at one end extending lengthwise thereof in line with 85 the slot and with a socket at the other end of the body for receiving the tongue of another main body, a T shaped coupling piece interchangeably mountable on the tongue and on a side face of the body with the head of the 90 T formation against the side face of the body, the leg of the T formation being bifurcated for receiving the tongue when the coupling piece is mounted at one end of the body and for receiving the tongue of an adjacent 95 body when the coupling piece is mounted on the side of the body, means for clamping the T shaped coupling piece in either of said positions, a detachable tongue for entering the socket for fitting the bifurcated leg, and 100 a T shaped coupling piece for the socket of another main body.

3. A frame unit for scaffolding, shorings, forms and the like comprising a main body formed with a lengthwise slot having a 105 tongue extending lengthwise thereof at one end and a socket at its other end for receiving the lengthwise tongue of a duplicate main member, and a coupling piece interchangeably mountable on the tongue at one end and on the side face of the main member, the coupling piece having openings arranged to receive a clamping member extending through the slot when the coupling piece is mounted 110 on one side face of the main member and an opening to receive clamping means when the coupling piece is arranged on another side face of the main body.

4. A frame unit for scaffolding, shorings, forms and the like comprising a main body 120 formed with a lengthwise slot having a tongue extending lengthwise thereof at one end and a socket at its other end for receiving the lengthwise tongue of a duplicate main member and a coupling piece interchangeably 125 mountable on the tongue at one end and on the side face of the main member, the coupling piece having openings arranged to receive a clamping member extending through the slot when the coupling piece is mounted 130

on one side face of the main member and an opening to receive clamping means when the coupling piece is arranged on another side face of the main body, said coupling piece being **T** shaped with the leg of the **T** being bifurcated for receiving a tongue, the head of the **T** being perforated for receiving said clamping means extending astride the main member when the coupling piece is mounted on the main body with the head against one side face of the main body and for receiving clamping means extending through the slot when the coupling piece is mounted on a face of the main body through which the slot opens.

5. A frame unit for scaffolding, shorings, forms and the like comprising a main body formed with a lengthwise slot having a tongue extending lengthwise thereof at one end and a socket at its other end for receiving the lengthwise tongue of a duplicate main member and a coupling piece interchangeably mountable on the tongue at one end and on the side face of the main member, the coupling piece having an opening arranged to receive a clamping member extending through the slot when the coupling piece is mounted on one side face of the main member and openings to receive clamping means when the coupling piece is arranged on another side face of the main body, said coupling piece being **T** shaped with the leg of the **T** being bifurcated for receiving the tongue, the head of the **T** being perforated for receiving said clamping means extending astride the main member when the coupling piece is mounted on the main body with the head against one side face of the main body and for receiving clamping means extending through the slot when the coupling piece is mounted on a face of the main body through which the slot opens, the main body being provided with teeth along one side thereof and the head of the **T** being provided with complementary grooves for receiving the teeth.

6. A frame unit for scaffolding, shorings, forms and the like comprising a main body formed of opposing channel iron members spaced apart and forming a slot, heads at opposite ends of the main body, one head being formed with a tongue projecting lengthwise from one end of the body and in line with the slot, and the other head having a tongue extending between the end portions of the channel iron of the main body and formed with a socket complementary to the first tongue, and a **T** shaped coupling piece having a bifurcated leg, the coupling piece being interchangeably mountable on the tongue with the tongue between the bifurcations and on a side face of the main member with the head of the **T** formation against said side face, the head being formed with perforations for receiving clamping bolts

when the coupling piece is mounted on either of the side faces of the main member.

7. A frame unit for scaffolding, shorings, forms and the like comprising a main member consisting of opposing channel irons spaced apart forming a slot between them and heads at opposite ends of the main member, the main member being formed with teeth on the side thereof through which the slot opens for coacting with the teeth of a duplicate main body lapping the same, the slots receiving clamping bolts.

In testimony whereof, I have hereunto signed my name, at Syracuse, in the county of Onondaga, and State of New York, this 6th day of July, 1931.
